FOLDING CHAIR

Elmer E. Frey, Los Angeles, Calif., assignor to
 Kittle Manufacturing Company, Los Angeles,
 Calif., a copartnership consisting of John P.
 Meehan, Rose B. Meehan, and Grace K.
 Leonard

Application February 12, 1936, Serial No. 63,518

2 Claims. (Cl. 155—140)

My invention relates to folding chairs and among its objects I aim to provide a folding chair which is strong, durable, easily folded and set up; one which, when folded, occupies a minimum of space; one which is comfortable and one which is composed of such construction and association of parts that it may be economically manufactured.

With the above objects in view, as well as others which will appear as the specification proceeds, my invention comprises the construction, arrangement and combination of parts as now to be fully described and as hereinafter to be specifically claimed, it being understood that the disclosure herein is merely illustrative and meant in no way in a limiting sense, changes in details of construction and arrangement of parts being permissible so long as within the spirit of the invention and the scope of the appended claims.

The accompanying drawings illustrate a preferred embodiment of my invention, and referring thereto:

Fig. 1 is a perspective of a chair embodying the invention (set up), parts of the seat and back members being broken away for illustrative purposes;

Fig. 2 is an enlarged fragmentary sectional view taken on line 2—2 of Fig. 1;

Fig. 3 is an enlarged view illustrating one of the back-post terminals (looking from the back of the chair towards the front);

Fig. 4 illustrates a variational form of my invention, in perspective, the chair being shown in partially collapsed position; and

Fig. 5 is a fragmentary view showing one of the front corner posts in vertical section.

Referring to Figs. 1, 2 and 3, the frame structure is composed of two identical side members generally designated by the letters D and E, respectively, and two support members generally designated F and G, respectively.

Side members D and E are each formed preferably of a single bar of channel iron concavo-convex in cross-section and bent to form a vertically extending front side post 11, 12, a horizontal arm rest 15, 16 and a vertically disposed back-support post 17, 18. Back corner post 19 is affixed at one of its ends to post 17 by being spot-welded in the channel thereof and a back corner post 20 is likewise affixed to post 18, these corner posts 19, 20 being likewise preferably composed of channel iron.

A collar 25, 26 (see Fig. 3) is affixed, as by spot-welding, to each of posts 19, 20. Only collar 25 is shown in Fig. 3, and from an inspection thereof it will be seen that the collar has a channel portion 25a which fits over and is spot-

welded to the convex front face of post 19. It has a flat front face to which seat frame element 37 (to be described) is attached, and projecting forwardly from its front face and formed as an integral part of the collar member there is a stop finger 27 whose function will be later described. Collar 26 is similarly formed and mounted and has a stop finger 28.

Support member F is preferably of channel iron of similar cross-section formed into substantially a rectangular frame comprising front and back bars 36, 37, respectively, seat support bar 35 and bottom bar 38—front bar 36 being pivotally connected adjacent seat bar 35 to front post 11 by means of a pivot pin 31 which passes through bar 11 and bar 36. Member G is likewise of channel iron similarly formed into a substantially rectangular frame comprising front and back bars 43, 44, respectively, seat support bar 42 and a bottom bar 45; front bar 43 being pivotally connected adjacent seat bar 42 to front post 12 by pin 41 which passes through both bar 12 and bar 43. The respective members F and G are each preferably integrally formed of a single channel bar bent into a substantially rectangular frame and whose ends overlap and are spot-welded together as shown at S and S'. Spot welded to post 11 and interposed between that post and bar 36 at the point of their pivotal connection is a flat-faced plate 31a, and likewise affixed to post 12 and interposed between that post and bar 43 at the point of their pivotal connection is a similar plate 41a.

Supports F and G are assembled in the form of an X, with their channels facing inwardly, and are pivotally connected together at the medial portions of their front and back bars respectively by pins 47, 48 for scissorwise movement with respect to each other. A flat-faced plate 49 is affixed to bar 43 and interposed between that bar and bar 36 at the point of their pivotal connection 47, and a like plate 50 is affixed to bar 44 and interposed between that bar and bar 37 at the point of their pivotal connection 48—the plates 49 and 50 being affixed to their respective bars by 45 being spot-welded thereto and the pin forming the pivotal connection for the respective bars passes through the plate. The front and back bars 36, 37 of member F each has an inwardly offset portion intermediate its ends so that member F may be mounted inside of frame G. Bar 37 is pivotally connected to the front flat face of collar 25 by pin 30 which passes through bar 37, collar 25 and post 19; and bar 44 is similarly pivotally connected to the front flat face of collar 26 55

by a pin (not shown) which passes through bar 44, collar 26 and post 20.

To permit collapse or folding of the chair, front bars 43 and 36 are pivotally attached to respective sliding bars mounted in the channels of the respective front posts. For instance bar 43 is pivotally connected, by pin 50, to bar 51 which is longitudinally slidably mounted in the channel of front post 11, a guard 52 being affixed, as by spot-welding, to post 11 over its channel to prevent lateral displacement of bar 51 from the channel. While the connection is not fully visible in the drawings, front bar 36 is likewise pivoted to an identical longitudinally slidable bar carried in the channel of front post 12 and which bar is held against lateral displacement from the channel of post 12 by a guard 54 spot-welded to post 12.

The chair is locked in its open or unfolded position by a pair of cross members 60, 61 each of which is hingedly connected at one end to a bracket 60a, 61a riveted to bar 45 in the channel thereof and hingedly connected at the other end to a bracket 60b, 61b riveted to bar 38 in the channel thereof. Members 60, 61 are each comprised of two sections hingedly connected together by pins 62, 63, a stop 64, 65 being provided on the top of the overlapping portion of each of members 60, 61 to lock the chair in open position when members 60, 61 are horizontal. Cross bar 66 affixed by rivets at one of its ends to bar 60 and at its other end to bar 61 laterally connects the bars 60, 61 and causes them to swing upwardly and downwardly simultaneously during folding and setting up of the chair.

As the seat member, I preferably employ a fabric 70 affixed at one side to bar 35 and at its other side to bar 42; and as the back rest I use a fabric 72 affixed at one side to posts 17-18 and at its other side to posts 19-20. It will be understood, however, that any foldable or collapsible material may be substituted for the fabric shown.

Fig. 1 shows my chair in open condition, ready for use. To fold it, one merely lifts cross member 60 slightly with his toe and compresses the arm rests together, which causes the X-shaped frame to fold in a scissorwise movement until frame members D and E come together. Conversely, to set up or unfold the chair, the arm rests are pulled apart until cross-bars 60, 61 are locked in a horizontal position.

In the variational form illustrated in Fig. 4 (illustrating the chair in semi-collapsed position) support frame members F and G are the same as before described and their components are given the same reference numerals. In fact the only respect in which this form differs from that previously described is in the back corner posts. Here, for instance, back corner post 80 is formed as a vertically downwardly extending continuation of the channel bar which forms front post 11, arm rest 15 and back-rest post 17; and back corner post 81 is likewise formed as a continuation of the channel bar which forms front post 12, arm rest 16 and back-rest post 18. Bar 37 is pivotally connected to post 80 at the point of the flat-faced plate 82 which is affixed to post 80 over the channel thereof (as by spot-welding) and is interposed between post 80 and bar 37 at the point of their pivotal connection. Bar 44 is likewise pivotally connected to post 81 at the point of the flat-faced plate 83 which is similarly affixed to post 81 and interposed between post 81 and bar 44 at the point of their pivotal connection. Longitudinally slidably carried in the chan-

nel of post 80 is a bar 84 which is pivotally connected at 86 to bar 44 adjacent its lower end, a guard 88 being spot-welded to post 80 over the channel thereof to prevent lateral displacement of bar 84 from the channel. Similarly mounted, in post 81, is a bar 85 pivotally connected at 87 to bar 37 adjacent its lower end, a guard 89 being spot-welded to post 81 over the channel thereof to prevent lateral displacement of bar 85 from the channel.

In this form of device, the back-rest support post 17 and corner post 80 form a U-bend 90 at the top of the chair and post 18 and post 81 also form a like U-bend 91, the channels of members 17, 80 and of 18, 81 facing each other throughout the vertical extent of posts 17 and 18. A fabric back-rest 95 having hems 96, 97, one at each of its ends, is slipped over the respective back corner posts and back-rest support posts as shown in Fig. 4. For illustrative purposes, the seat fabric 70 is shown in dotted lines in Fig. 4.

It will be seen that the construction, arrangement and combination of parts above described provide a chair of extremely sturdy construction. By integrally forming the major frame elements 25 of channel bars, great economy of manufacture is possible without the chair being unduly heavy and without sacrifice of strength. Although the frame members are composed principally of concavo-convex channel iron, uniformly and easily 30 operable pivotal connections are provided between various of the frame elements by virtue of the flat-faced plates interposed between the abutting convex and concave faces at the points of the various pivotal connections. The only 35 sliding connections are those at the bottom of the chair where the members F and G are connected to the respective sliding bars carried in the respective front corner post channels, and all the other pivotal connections are a substantial 40 distance below the arm rests. Therefore, since the chair is folded and opened by urging the arm rests apart or together, as the case may be, there is no sliding part nor any pivotal connection to pinch the operator as is usually the 45 case with folding chairs. When folded, the chair utilizes a minimum of space.

I claim:

1. In a folding chair, a seat supporting element comprised of two rectangular seat-supporting frames pivotally connected together for scissorwise movement in a vertical plane with respect to each other and each having an upper and a lower horizontally disposed end element, the lower one of which forms a foot member and the upper one of which forms a seat support, a pair of side frame elements each presenting a corner post extending upwardly from a foot member, a slider telescopically mounted in the lower end of each said post and being telescopically extended below the lower end of said post, each of said rectangular frames being pivotally connected adjacent its foot member to the slider in one of said corner posts and pivotally connected adjacent its seat support to the other of said corner posts, and a brace member extending crosswise of the chair from one to the other of the foot members of the rectangular frames to prevent their relative movement.

2. In a folding chair, a seat supporting element comprised of two rectangular seat-supporting frames pivotally connected together for scissorwise movement in a vertical plane with respect to each other and each having an upper and a lower horizontally disposed end member,

the lower one of which forms a foot member and the upper one of which forms a seat support; side frames, one at each side of the chair, each being comprised of a corner post extending from a 5 foot corner of one of the seat supporting frames upwardly to a point spaced above the upper end member of the other seat supporting frame, thence backwardly to form an arm rest and thence downwardly to the upper end of the last 10 mentioned seat supporting frame, said side frames being pivotally connected to the seat supporting element adjacent the said seat supports, a stop finger carried by each side frame and co-

operating with the seat supporting element to prevent collapse thereof in one direction, a slide bar telescopically mounted in the bottom end of each corner post, one of said seat supporting frames being pivotally connected adjacent its 5 foot to one of said slide bars and the other of said seat supporting frames being pivotally connected adjacent its foot to the other of said slide bars, and a brace member extending cross-wise of the chair from one to the other of the 10 foot members of the seat supporting frames to prevent their relative movement.

ELMER E. FREY.
